PIN CARRIAGE MECHANISM

Tord Erik Daniel Bilde, Stockholm, Sweden

Application July 13, 1935, Serial No. 31,258
In Sweden January 4, 1935

3 Claims. (Cl. 235—60)

This invention relates to a ten-key calculating machine and it aims to provide a generally improved and more compact embodiment operable with greater efficiency.

5 A prime object is to provide a calculating machine of this character having a movable, settable pin carriage wherein the settable pins are disposed in a plurality of digital groups, preferably vertical, each group having a plurality of pin columns, usually three, whereby a narrower carriage may be utilized.

Another object is to provide a construction wherein the differential digital actuators are controlled by abutment with the settable pins, the pins of each row coating with a different projection or abutment of the associated differential digital actuators, the pins being arranged so that the operation of the escapement will dispose a different group of the settable pins, in operative relation to each differential digital actuator, through each movement of the escapement.

A further object is to provide a novel structure wherein each key actuates a pusher rod and the pusher rods in turn actuate the pins of the novel groups of settable pins.

Various additional objects and advantages will become apparent from a consideration of the description following, taken in connection with the accompanying drawings of an operative embodiment.

In said drawings:

Fig. 1 is a view partly in side elevation and partly in section through the improved calculating machine;

Fig. 2 is a view showing the settable pin carriage in connection with differential digital actuators;

Fig. 3 is a transverse sectional view taken substantially on the line 3—3 of Fig. 1;

Fig. 4 is a plan view of the parts of Fig. 1;

Fig. 5 is a view showing a modified form of settable pin and portions of the pin carriage in vertical transverse section;

Fig. 6 is a view taken substantially on the line 6—6 of Fig. 5;

Fig. 7 is a fragmentary view in cross section of the pin carriage, showing the use of a modified form of the pin;

Fig. 8 is a side elevation of the carriage and settable pins of the form of Fig. 7;

Fig. 9 is a view in horizontal section, showing the employment of my improvements in a machine having slideable rather than turnable differential digital actuators;

Fig. 10 is a top view of the slideable differential digital actuator employed in Fig. 9; and

Fig. 11 is a side elevation of the setting up lever of Fig. 9, with associated parts.

Referring specifically to the drawings wherein like reference characters designate like or similar parts, a suitable casing is provided at A which mounts ten keys 43 having vertically slideable rods 58 normally resting on a horizontally disposed 5 depressible plate 64. Each key 43 is separately 10 depressed as is usual in machines of the ten-key type.

Suitably guided by the casing A and by a guide casing 47, are ten pusher rods 45. Said pusher rods, as best shown in Fig. 3, are arranged in a 15 plurality of rows, preferably vertical and three in number with the center row having four pusher rods and the outer rows having three pusher rods.

Each of said pusher rods 45 is connected to a different key rod 58. By way of example, each 20 key rod 58 has a bell crank lever 44 pivoted to it by a pin and elongated slot connection as at 59. Such bell crank levers are pivoted at 61 on horizontal axes within the casing A. Each bell crank lever 44 has its other arm connected by a pin and 25 elongated slot as at 62, or the equivalent, to a different pusher rod 45.

A displaceable spring impelled carriage is shown at 48, mounted for sliding movement transversely of or in front of the pusher rods 45. Said carriage 48 may be generally U-shaped in cross section, as shown in Fig. 1, and have its free edges 30 slidably mounted in grooves 60 on a stand or support 48b fixed to or stationary on the frame of the machine as at 48a.

Said carriage 48 slidably mounts settable pins 46 in slots 46a provided in opposite walls of the carriage. Said settable pins 46 are arranged, as shown in Fig. 2, in groups of ten, corresponding to the arrangement of the pusher rods 45. The 40 carriage 48, under control of a suitable escapement, is adapted to position one of the ten groups of settable pins 46, upon each escaping movement of the carriage in alignment with the pusher rods 45. Hence, each time a key 40 is depressed, one 45 of the pusher rods 45 will be moved forwardly and will actuate or project one pin of the group of pins 46 then in line with the pusher rods 45, following which, the escapement will be operated to displace the next succeeding group of ten pins 50 16 in line with the pusher rods 45, of which group one pin will be projected and the carriage again escape, etc.

The escapement of the carriage 48 is controlled 55 through the depression of the previously men-

tioned plate 64. Pivoted to said plate 64 is a link 51, which is also pivoted as at 59 to the frame of the machine. Also pivoted to the plate 64 is an arm of a bell crank lever 52. Bell crank lever 52 is pivoted at 50a to the frame of the machine. One arm of bell crank lever 52 is pivoted to a link 54 having a slot through which projects an arm 54a on a shaft 53 so that depression of the plate 64 will cause the shaft 53 to rock on its longitudinal axis and thus actuate a double ended escapement pawl 55, shown in Figs. 1 and 2, which cooperates with equidistantly spaced teeth 65 on the lower edge of the carriage 48, and which permit the carriage to escape, upon each 10 rocking of the escapement shaft 53, a distance which disposes a different group of ten settable pins 46 in line with the pusher rods 45.

Those settable pins 46 which are projected by the pusher rods 45, coat with differential digital 20 actuators 57 shown in the form of disks or plates journaled on an actuator shaft 56. There is a differential digital actuator 57 for each group of ten settable pins 46. The settable pins 46 of the central vertical row of each group coat one with 25 a projection or abutment 66 of the adjacent actuator 57 while the pins 46 of the remaining or outside vertical rows of the same group coat with the projections or abutments 67 and 68, respectively, on opposite sides of the actuator.

30 The differential digital actuator mechanism may be of the type disclosed in my co-pending application, Serial No. 31,259, filed July 13, 1935.

Retraction or restoration of the pins 46 to normal position is effected by the engagement of 35 the projecting pins with an inclined or cam plate 198, as the carriage 48 moves back to starting position. It may be pivoted on a vertical axis at 191 so that if the carriage 48 does not move far enough to retract all of the settable pins 46, 40 means on the carriage may operate to swing the plate 198 against the projecting pins, and slide them back to starting position.

In the operation of the machine, it will be realized that each time one of the ten keys 43 is depressed, a pusher rod 45 will be moved forwardly, projecting or forwardly sliding the settable pin 46 in its path. The same movement of the key 43 depresses plate 64, rocks the bell crank 52, lowers the link 54 and through its connection 50 with crank 54a turns the escapement shaft 53 on its longitudinal axis and thereby moves the pawl 55 so that the carriage 48 will escape one space or the distance between two teeth 65, corresponding to the spacing of the groups of ten 55 settable pins 46. The carriage remains in this position and a corresponding escapement movement of the carriage takes place with the projection of a pin 46 in each group, each time a key 43 is depressed. The calculating and/or printing operations are effected by the differential digital actuators 57, through coaction of their abutments 66, 67 and 68 with the projected settable pins. Upon return of the carriage to its initial or starting position, the pins 46 which are 65 in projected position will be restored to their initial position preparatory to the succeeding operation.

A modified form of settable pin which may be used in place of those at 46 is disclosed in Figs. 5 and 6 at 95. This pin 95 is shown as slidably mounted in spaced apart walls 48a and 48b of a carriage corresponding to that at 48. Lugs 96 extend from opposite end portions of the pin 95 and furnish shoulders adapted to abut the walls 75 48a and 48b to limit the movement of the pin in

opposite directions. One of the lugs 96 of each pin is adapted to be brazed or welded to the remainder of the pin following assembly of the pin in the walls 48a and 48b. In addition, such modified pin 95 may carry a resilient or spring latch 5 97, which is preferably made of wire and has one end anchored in an opening 99 of the pin. This latch 97 has a sinuous portion providing depressions 100 and 101 which, through the yielding movement of the pin as it slides through openings 102 and 103 of the arm 48a and 48b, clip into engagement with the wall 48b to hold the pin in projected and retracted positions, respectively.

In Figs. 7 and 8, a modified form of carriage and settable pins is disclosed. The carriage in this form has spaced apart walls or plates 88 and rollers 89 journaled between them on transverse rods 90 secured to the frame of the machine. The walls 88 have openings 89 therethrough in 20 which settable pins 91 are slidably disposed. These pins 91 function like those at 46 and 97, being made of a single strand of wire or other resilient material, having tines 92 and 92' tending to separate at their unconnected ends. The tine 92' at its free end has a sinuous portion like that at 97, providing depressions 100' and 101' adapted to clip into engagement with the adjacent wall 88 at the slot 88', in a projected and retracted position of the pin, respectively. It is 30 clear that the carriage is provided with ten groups of ten settable pins, arranged or positioned exactly like those at 46 and the same is true of the number and arrangement of the pins 95 with respect to their carriage. 35

Referring to Figs. 9 to 11, a modified form is disclosed wherein the differential digital actuators are slidable, being particularly vertically movable, as contrasted with the rotatable differential digital actuators hereinbefore described. 40 In this modified form, a casing is employed to form a base 1 and a cover or upper section 2. The vertically slidable differential digital actuators are shown at 10, having teeth at 40 coacting with calculating wheels as at 62 with which is 45 associated a tens movement mechanism 66. The slides or differential digital actuators 10 through suitable specific mechanism actuate printing means at 38, coacting with a web 96 passing from a paper roll 86 to a platen roller 81, such rollers 50 being mounted on shafts 84 and 80, respectively.

Each slide 10 has a shoulder or projection 51 on one side thereof, a shoulder or projection 52 on the opposite side thereof, and a shoulder 53 in the plane of the slide proper and, hence, between 55 the planes of the abutments or projections 51 and 52.

A settable pin carriage is shown at 35 provided with upper and lower rollers 35 and 36, which travel on rods 34 disposed transversely 60 of the casing and fastened, for instance, to the sides of the cover section 2. Such carriage 35 mounts settable pins 30 corresponding to those at 46 or 95, being identical in number and arrangement. Thus, one row of each digital group of the pins 30 will form abutments for the projection 51, the other row of such digital pins 30 will form abutments for the projection 52, while the central row of pins 30 will form abutments for the shoulder 53, the pins 30, thus, coacting with the differential digital actuators 10 in the same manner which the pins 46 or 95 coat with the rotatable differential digital actuators 57. 65

Pusher rods 24, ten in number and arranged identically with the pusher rods 45, and as de- 70 75

tailed in Fig. 3, are slidably disposed in openings 39 of a bracket or guide 28 fastened to the side walls of the cover 2 of the casing.

5 Adjacent the other ends of said pusher rods 24, bell crank levers 97 are pivoted at 23. Such bell crank levers are pivoted on rods 18 fastened under casing cover section 2, and the remaining arms of such levers are pivoted at 22 to the vertically slidable shafts 16 or depressible keys 17 extending 10 above an opening 4 in the cover section 2 through which the pin shafts 16 slide. There are ten of the keys 17 conforming to the arrangement of the keys 43 of the previous form of the invention as detailed in Fig. 4.

15 Said Figs. 9 to 11 disclose a modified form of the invention employing substantially the same pin carriage mechanism as the other forms in cooperation with differential actuator devices of a different type. The differential actuator devices are no part of the present invention and therefore are not described in detail.

Various changes may be resorted to provided they fall within the spirit and scope of the invention.

What I claim is:

1. In a calculating machine of the ten key type, a pin carriage and settable pins carried by said carriage arranged in digital groups, said pins of each digital group being arranged in a 5 plurality of rows.

2. In a calculating machine of the ten key type, differential actuators, a pin carriage and settable pins carried by said carriage arranged in digital groups, said pins of each digital group 10 being arranged in a plurality of rows, and a plurality of abutment means on said differential actuators each cooperating with one of said rows of pins.

3. In a calculating machine of the ten key type, 15 a pin carriage and settable pins carried by said carriage arranged in digital groups, said pins of each digital group being arranged in a plurality of rows, in combination with a differential actuator for each digital group of pins, each group 20 having the pins thereof arranged in columns shiftable in the path of movement of the corresponding differential actuators.

TORD ERIK DANIEL BILDE.
